UNITED STATES PATENT OFFICE

WALTER E. LIPPERT, OF HEWLETT, NEW YORK, ASSIGNOR TO SAMUEL BONAT & BRO.,
OF NEW YORK, N. Y., A COPARTNERSHIP

DESIGN FOR A PEDESTAL DOME FOR HAIR PERMANENT WAVING MACHINES

Application filed October 6, 1931. Serial No. 41,318. Term of patent 7 years.

To all whom it may concern:

Be it known that I, WALTER E. LIPPERT, a citizen of the United States, residing in Hewlett, county of Nassau, Long Island, State of New York, have invented a new, original, and ornamental Design for Pedestal Dome for Hair Permanent Waving Machines, of which the following is a specification, reference being had to the accompanying drawings, forming part thereof.

In the drawings Figure 1 is a plan view of the pedestal dome for hair waving machines showing my new design, and

Figure 2 is a side elevation of the same.

I claim:

The ornamental design for a pedestal dome for hair permanent waving machines, as shown.

WALTER E. LIPPERT.
